UNITED STATES PATENT OFFICE.

JAMES A. JENSEN, OF PHILADELPHIA, PENNSYLVANIA, ASSIGNOR TO QUAKER CITY IRON WORKS, OF PHILADELPHIA, PENNSYLVANIA, A CORPORATION OF PENNSYLVANIA.

CLOSURE FOR FILLER OPENINGS.

Application filed February 7, 1925. Serial No. 7,524.

This invention relates to closures for filler openings and it has more particular reference to that type associated with manhole covers of portable tanks for oils and the like 5 of a combustible and explosive nature, said closures being usually fitted with a vent functional as an emergency escape for vapor as well as the admission of air when liquid is drawn-off thereby preventing the creation 10 of a vacuum in said tank.

An object of this invention is to provide an improved closure of the typified character, the vent whereof is fitted with a removable fire screen plug.

Another object of my invention is to connect a closure of the character stated to the 15 filler neck or surrounding structure in a manner permitting free rotation while retaining hinged relation thereto.

How the foregoing objects are attained will be apparent from the following detailed 20 description of one practical embodiment of my invention, reference being had to the accompanying drawings constituting a part 25 hereof, and in which like designating characters distinguish corresponding parts in all the views.

Fig. I, is a side view of the rear portion 30 of an automotive oil tank or truck, the filling closures whereof embody my invention.

Fig. II, is a broken top plan view of a manhole cover and filler closure embracing the present improvements.

Fig. III, is a diametric section of the 35 same; and,

Fig. IV, is an enlarged longitudinal section through the removable fire screen.

Referring more in detail to the drawings the rear portion of a self-propelled oil tank 40 truck is comprehensively designated by the numeral 5, the same including separate sections 6 mounted in conventional manner upon a chassis 7, and provided with the customary side walks 8, and bucket box 9; while 45 10 designates one of the traction wheels. Each individual tank section 6 is provided with a manhole frame 11—secured thereto in any of the well known ways—having a screw-threaded upper part adapted to accommodate the complementarily threaded 50 annular flange 12 of a manhole cover 13, with interposition of a gasket 14 to ensure a tight joint. The manhole cover 13 is pro-

vided with upstanding projections 15 by means of which it may be manipulated in 55 the well known way for removal and replacement, and said cover is fashioned with a concentric annular lip 16. This lip 16 affords a filler opening which is internally 60 screw-threaded to receive the similarly threaded flange 17 of a closure cap 18, having an embossment 19 with diametrically opposed lateral handles 20 by means of which said closure cap is screwed and unscrewed relative to the manhole cover 13. A gasket 65 21 is interposed between the shoulder surrounding the flange 17 and the top of the annular lip 16 to maintain a tight joint.

The closure cap 18 is connected to the manhole cover 13 by means of a shackle-ring 22 70 preferably made of spring wire and of a diameter to freely fit a suitably shaped groove 23 provided about the embossment 19 aforesaid. As best seen in Figs. II and III, the shackle-ring 22 is fashioned from a 75 length of suitable gauge wire medially configured to constitute said ring with the free ends 24 laterally brought into impingement, angularly bent and retroverted to afford elongated eyes 25 loosely accommodated between spaced vertical lugs 26 on the manhole cover 13, hinged connection being established through the medium of a split-pin 27 in the well known way. Thus it will be readily understood that the closure cap 18 85 may be freely removed from—and replaced in—the filler opening 16 without fear of disconnection relative to the manhole cover 13 and incident prevention of loss or misplacement. 90

In the center of the closure cap embossment 19 and reinforced by inner and outer concentric bosses 28, 29 respectively, as best seen in Fig. III, is a screw-thread bore 30, the outer portion whereof receives the complementarily threaded nipple 31 of a conventional vent-device 32. Associated with the vent-device 32, is a removable fire screen plug comprehensively designated by the numeral 33, and illustrated to best advantage 95 by Fig. IV. This plug 33 comprises a screw threaded ferrule 34—adapted for removable connection in the lower inner end of the above referred to bore 30—with a flared end 35 and suitably configured (hexagonal for 100 example) enlargement 36, whereby it may 105

be conveniently manipulated by a wrench. The flared end 35 is also provided with an annular extension 37 affording a seat 38 for a reticulate material screen 39 of fine mesh, 5 the same being held securely in place through the medium of a clamping ring 40 and the inward knurling of said annular extension at 41, as will be readily understood by those conversant with the art. Obviously the re- 10 movable filter attachment 33 prevents the ignition of gasoline or other vapors in the tank sections 6 in case a flame is brought near the vent 32. The wire screen 39 of fine mesh prevents the flame from igniting the 15 vapors in similar manner, that the wire screen around a miner's oil lamp prevents the flame thereof from igniting the surrounding gases in a mine.

From the foregoing it will be readily understood that by my invention I have provided a simple and effective closure for filler openings, the inherent usefulness whereof is so obvious as not to require further explanation, while the particular application 25 shown and described is by way of example only, as other embodiments will suggest themselves without departing from the spirit of my said invention or sacrificing any of its advantages.

Having thus described my invention, I 30 claim:

1. In a closure for the filler openings of manhole covers comprising a flanged cap with an embossment and diametrically opposed manipulating handles, the embossment 35 having an axial screw-threaded bore and a vent device threaded into the outer end of the aforesaid bore, the combination of an adjustable ferrule screwed into the inner end of the bore, said ferrule embodying a flared 40 outer end with an annular extension for reception of a reticulate disk held in place by a clamping ring and inward knurling of the extension peripheral edge.

2. A fire screen attachment for the filler- 45 opening closures of manhole covers, comprising an externally screw-threaded ferrule having one end designed to provide a flare with a polygonal enlargement and an annular extension, a reticulate disk seating in the 50 extension, and the free end of said annular extension being inwardly knurled to lock said reticulate disk securely in place with interposition of a clamping ring.

In testimony whereof, I have hereunto 55 signed my name at Philadelphia, Pennsylvania, this 2nd day of February, 1925.

JAMES A. JENSEN.
